UNITED STATES PATENT OFFICE

2,441,204

APPARATUS FOR FILLING CONTAINERS

Lee Nusbaum, Philadelphia, Pa.

Application May 17, 1944, Serial No. 535,933

4 Claims. (Cl. 285—210)

1

In the filling of containers under pressure and particularly where the container is to be filled with a fluid material, such as a propellant, which is in liquid form at the storage pressure in the container but in a gaseous state at normal atmospheric pressure, many difficulties have heretofore been encountered. While it is possible to fill a single container with such material it has heretofore been exceedingly difficult to fill a plurality of containers simultaneously while at the same time maintaining an equal distribution to and in the respective containers. It is also frequently desired to include as a portion of the contents other materials in fluid form for distribution by the propellant as aerosols. These other materials may be introduced separately or with the propellant as desired.

This invention therefore relates to apparatus for filling containers, and more particularly to apparatus for simultaneously filling a plurality of containers each with an equal quantity of material.

The nature and characteristic features of the invention will be more readily understood from the following description, taken in connection with the accompanying drawings forming part hereof, in which:

Figure 1 is a top or plan view of a preferred embodiment of the present invention;

Fig. 2 is a view in elevation of the apparatus shown in Fig. 1;

Fig. 3 is a vertical central sectional view through a manifold employed in connection with the invention; and

Fig. 4 is a horizontal sectional view taken approximately on the line 4—4 of Fig. 3.

It should, of course, be understood that the description and drawings herein are illustrative merely, and that various modifications and changes may be made in the structure disclosed without departing from the spirit of the invention.

Referring more particularly to the drawings, the containers 10 which it is desired to fill with fluid materials at pressures above atmospheric, preferably consist of pressure vessels capable of withstanding the desired pressures in accordance with the filling material. These pressure vessels 10 are preferably of metal, may be provided with safety plugs 11 or the like for relief if the internal pressure becomes excessive, and are preferably also provided with suitable valves 12 having manually operable handles 13 for controlling the discharge of the contents, and also for use in filling or refilling as hereinafter pointed out.

The valves 12 have threaded nipples 14 to which suitable fittings 15, internally threaded, are adapted to be detachably secured. The fit-

2

tings 15 are adapted for connecting distributing pipes 16 to the nipples 14.

The distributing pipes 16 also each have connected thereto suitable fittings 17 and 18. The fittings 17 are internally threaded for engagement with threaded nipples 19 on the fittings 18 and the fittings 18 also have threaded nipples 20 for engagement in internally threaded portions 21 in a manifold 22. The manifold 22 is preferably formed of a suitable block of material. The manifold 22 preferably includes a central distributing chamber 25 from which a plurality of horizontal passageways 26 are provided leading radially from the central chamber 25 at the same elevation to the interiors of the fittings 18. The passageways 26 preferably serve as restrictions for controlling the delivery of the fluent material.

The lower end of the distributing chamber 25 below the inner terminal ends of the passageways 26 is preferably dished as at 27, it having been found that this dished shape aids in the equal distribution of the fluid materials to the containers 10. A supply connection 30 is provided having a threaded portion 31 for connection to the manifold 22 and to the upper end of the distributing chamber 25. The supply connection 30 may, if desired, have a screen 33 of metal or other suitable material secured to the lower end thereof. The supply connection 30 also has a threaded nipple 32 for the connection thereto of a suitable supply pipe 34.

The supply pipe 34 preferably has connected thereto, through a flexible connection 35, a plurality of pipes 36, 37 and 38, the flow through which is controlled by valves 39, 40 and 41. The pipes 36 and 37 may be employed for supplying different fluent materials and the pipe 38 may be connected to a source of vacuum for exhausting prior to the introduction of the fluent materials under pressure, or if desired for the introduction of other fluent materials.

A weighing scale pan 45 may be provided for use in determining the weight of the material supplied to the containers 10.

The mode of operation of the apparatus in accordance with the present invention will now be pointed out. The containers 10 with the safety plugs 11 in place and with the valves 12 mounted thereon are each in turn secured in position, the fittings 15 being brought into engagement with the nipples 14 and tightened.

The valves 12 of the containers are all opened by means of the handles 13, and the weighing scale pan 45 is placed in position to support the containers as thus mounted. The flexible connection 35 permits ascertaining the initial weight in unfilled condition of the containers 10 and associated structure movable therewith.

The valves 39 and 40 are in closed condition.

The valve 31 may be opened for exhausting through the pipe 38 the interior of the system including the containers 10, the distributing pipes 16, the manifold 22, and the supply pipe 34 preparatory to supplying the material for filling the containers 10. When the exhausting has been completed the valve 41 is closed. The valve 40 may then be opened for supplying fluent material from the pipe 37 through the pipe 34 to the distributing chamber 25. This material, if desired may be an insecticidal constituent, such as pyrethrin, or may be any other desired material. The fluid material from the pipe 37 is delivered through the pipe 34 to the distributing chamber 25 of the manifold 22, then passes outwardly through the passageways 26, which aid in the proportional distribution, through the fittings 18 and 17 and the distributing pipes 16, and through the fittings 15 and the valves 12 to the interiors of the containers 10. When the desired quantity of material to be supplied from the pipe 37, has been introduced, as indicated by the action of the scale pan 45 the valve 40 is closed.

If desired the valves 12 may be closed and the distributing pipes 16, the manifold 22 and the supply pipe 34 may again be exhausted.

To introduce another filling material, with the valves 12 open the valve 39 is opened for the delivery of fluent material from the pipe 36 and through the pipe 34 in the same manner as heretofore pointed out. This material, if desired, may be a propellant such as Freon, methyl chloride or the like. When the desired total quantity of material has been delivered into the containers 10 as indicated by the increased weight of the containers and their associated structure upon the scale pan 45 the valve 39 is closed.

The valves 12 are then closed by means of the handles 13 and if desired the valve 41 may again be opened for exhausting the material remaining in the pipe 34, in the manifold 22 and in the distributing pipes 16.

The containers 10 may then be removed by disconnecting the fittings 15 and are ready for the installation of nozzles (not shown) if desired or for shipping. The same procedure is employed for refilling the containers 10 as for the initial filling and it will be clear that the operations may be performed quickly and with a minimum of waste or discharge of material into the atmosphere. At the same time it has been found in practice that with a plurality of containers equal quantities of different fluent materials desired will be delivered to the respective containers within close tolerances.

I claim:

1. In an apparatus for simultaneously filling a plurality of containers from a source of liquefied filling material under pressure, a manifold block member connected to said source and having separate fluid delivery connections to each of said containers, said manifold block being closed at the bottom and having a central fluid distributing chamber formed therein, a central filling material inlet at the top of said chamber, and a plurality of horizontal restricted flow controlling passageways formed in said block member and extending radially outwardly from said chamber at the same elevation, each of said passageways being in communication with one of said fluid delivery connections, and the portion of said chamber beneath the inlets of said passageways being of concave shape.

2. In apparatus for simultaneously filling under pressure a plurality of fluid containers from a source of liquefied filling material under pressure, the means for effecting uniform filling of the containers including a manifold member connected to said source and having separate fluid delivery connections to each of said containers, said manifold member having a central fluid distributing chamber, a central filling material inlet at the top of said chamber, and a plurality of restricted flow controlling passageways extending horizontally radially outwardly from said chamber at the same elevation for regulating the flow of filling material to said containers, each of said passageways being in communication with one of said fluid delivery connections, and the portion of said chamber beneath the inlets of said passageways being of concave shape.
3. In apparatus for simultaneously filling under pressure a plurality of fluid containers from a source of liquefied filling material under pressure, a one piece manifold block member connected to said source and having separate fluid delivery connections to each of said containers, said manifold block member being closed at the bottom and having a central fluid distributing chamber formed therein, a central inlet at the top of said chamber in communication with the said chamber, and a plurality of horizontal flow controlling passageways extending radially outwardly from said chamber at the same elevation, each of said passageways comprising a fixed restriction formed in said manifold block member and in communication with one of said fluid delivery connections, the portion of said chamber beneath the inlets of said passageways being of concave shape.

4. In apparatus for simultaneously filling under pressure a plurality of fluid containers from a source of liquefied filling material under pressure, a manifold connected to said source and having separate fluid delivery connections to each of said containers, said manifold having a central fluid distributing chamber, a central inlet at the top of said chamber in communication with said chamber, and a plurality of flow controlling passageways extending radially outwardly from said chamber for regulating the flow of filling material to said containers, each of said passageways being in communication with one of said fluid delivery connections, and the portion of said chamber beneath the inlets of said passageways being of concave shape.

LEE NUSBAUM.
